COLLAPSIBLE BED

Ben McKeithan Graham, Tupelo, Miss.

Application August 7, 1935, Serial No. 35,176

2 Claims. (Cl. 5—2)

The invention relates to a bed and more especially to a collapsible or extensible bed.

The primary object of the invention is the provision of a bed of this character, wherein the same when collapsed will be concealed within a cabinet, the latter functioning as a dresser or other article of furniture and thus the collapsing of the bed affords space within an enclosure and such bed will have disappeared, the operation of 10 the bed being simple and assures easy control in the extending or collapsing of the same.

Another object of the invention is the provision of a bed of this character, wherein on the collapsing thereof the mattress carried thereby 15 will be automatically folded into compact form and the latter with the bed will be concealed within a cabinet or the like, the bed being of novel construction.

A further object of the invention is the provision 20 of a bed of this character, which is comparatively simple in construction, thoroughly reliable and effective in its operation, strong, durable, readily and easily handled, assuring compactness when 25 collapsed condition and inexpensive to manufacture.

With these and other objects in view, the invention 30 consists in the features of construction, combination and arrangement of parts as will be hereinafter more fully described, illustrated in the accompanying drawings, which disclose the preferred embodiment of the invention and pointed 35 out in the claims hereunto appended.

In the accompanying drawings:

Figure 1 is a vertical sectional view through 35 a cabinet showing the bed constructed in accordance with the invention a part thereof and extended.

Figure 2 is a fragmentary side elevation showing 40 the bed partly folded.

Figure 3 is a sectional view on the line 3—3 of Figure 2 looking in the direction of the arrows.

Figure 4 is a vertical sectional view through 45 the cabinet showing the bed collapsed or folded.

Figure 5 is a front elevation thereof.

Figure 6 is a bottom plan view of the bed when 50 extended.

Similar reference characters indicate corresponding parts throughout the several views in the drawings.

Referring to the drawings in detail, A designates generally a cabinet having at the top thereof a drawer 19 while provided in this cabinet below the said drawer is a compartment 11 which 55 opens through the front of the said cabinet, the

drawer being manipulated from the front of the latter.

Adapted to occupy the space 11 within the cabinet A is the collapsible bed which comprises a foot section or board 12 having connection with 5 lazy tongs B, these being at opposite sides of a canvas mattress support 13 and each lazy tong includes the crossed levers 14 pivoted at their crossing points as at 15 while the levers at their meeting ends are pivoted together at 16, these 10 being in the form of rods and underlie the support 13 at a distance considerably below the same.

The tongs B at one end have the sliding connections at 17 with the sides of the cabinet A inwardly of the space 11 therein and likewise these 15 tongs B at the other end through linkage 18 and 19 have pivotal connection at 17' with the foot section or board 12 at the brackets 20 thereon.

The support 13 through the instrumentality of 20 the end springs 21 connected therewith and with the pivot 17 and to a cross piece fixed to and between the brackets 20, respectively is sustained 25 under tension when the bed is extended while supplementing the support 13 are spring tensioned straps 22, these underlying the said support 13 and have connection with the lazy tongs B, the tensioning of said straps 22 being lateral so that the support 13 will be prevented from 30 sagging on the extending of the bed.

When the bed has been collapsed by pushing inwardly upon the section 12, it will be concealed within the space 11 in the cabinet A.

Associated with the end portions of the lazy tongs B are lifter levers 23 and 24, respectively, 35 the latter carrying connections 17 while the levers 23 are swingingly connected to the outermost pivot 15 of said tongs. The levers 24, each by the connection 17 slides in a curved slotted track 25, there being two of these fixed to opposite sides of the cabinet and a link 26 pivoted to said lever 24 and at 27 to the extension 28 of one of the levers 14 while the levers 23 each is pivoted at 30 to a link 31 pivoted at 32 to an extension 33 of another of said levers 14. These 40 levers 23 and 24, which are in pairs, each carries at the inner ends a coiled tensioned lifter strap 34 which is disposed transversely of a mattress 35 when upon the support 13 so as to be disposed between the latter and said mattress 50 at a breaking joint 36 between folding sections 37 of said mattress 35 so that when the bed is collapsed the mattress 35 will automatically fold into compact form under the action of the levers 23 and 24 and the lifter strap 34 connecting with 55

each pair of said levers 23 and 24 as is clearly shown in Figures 2 and 3 of the drawings.

When the bed is to be occupied on the extending of the lazy tongs B the mattress 35 will automatically unfold and be supported upon the support 13 which is rendered taut when the lazy tongs B are extended, the levers 23 and 24 being lowered on the extension of said lazy tongs. When the bed is collapsed under the action of the lazy tongs B the levers 23 and 24 will be swung upwardly and in this manner automatically folding the mattress 35 so that the latter and the said bed will become concealed within the space 11 in the cabinet A as is shown in Figure 4 of the drawings. The links 18 are of considerably greater length than the links 19, the latter being slightly curved and are pivoted at 19' to the end toggle levers of the lazy tongs B. These links 18 and 19 when the lazy tongs B have been extended will sustain the foot section or board 12 in a perpendicular position, there being no possibility of the closing of the lazy tongs B accidentally when the bed is occupied due to the fact that the weight upon the mattress through such occupancy is distributed throughout the length of the lazy tongs laterally to opposite sides thereof and the strain is placed at the crossing points 15 of the levers 14 while strain in a longitudinal direction is nil.

The drawer 10 carries handles 38 and the foot section or board also carries the handles 39. The bed is extended and collapsed in an easy manner through the operation of the lazy tongs B and also the mattress 35 is automatically folded and unfolded as hereinbefore set forth.

It is, of course, understood that the mattress 35 is supported by the spring tensioned strap when occupied for sleeping or resting purposes. The links 26 and 31 through their connection with the lazy tongs B and the levers 23 and 24 will automatically swing the said levers vertically on the folding and unfolding of the bed, the levers 24 being slidably connected by the connections 17 with the tracks 25 so that the lazy tongs when collapsed will be housed well within the cabinet A.

What is claimed is:

1. A collapsible bed comprising a cabinet having a displaceable front forming a foot board, a pair of lazy-tongs arranged between the cabinet and the foot board and having connection

therewith in spaced parallel relation to each other for extension and contraction without and within said cabinet, a flexible mattress support yieldably fitted at opposite ends with the connections between the lazy-tongs, the cabinet and the foot board, respectively, a sectional, foldable mattress on said mattress support and having fold lines remote from its ends, lifting levers on each side of the lazy-tongs pivoted on the lazy-tongs near each end thereof, respectively, and extending toward the center of the lazy-tongs, means operatively connecting the outer ends of said levers with the lazy-tongs whereby retracting the lazy-tongs lifts the inner ends of the levers, and resilient lifting members interposed between the mattress and mattress support and connecting each lever with a corresponding lever on the opposite side whereby on retraction of the lazy-tongs the mattress will be lifted along fold lines remote from the ends thereof and folding of the mattress assisted.

2. A collapsible bed comprising a cabinet having a displaceable front forming a foot board, a pair of lazy-tongs arranged between the cabinet and the foot board and having connection therewith in spaced parallel relation to each other for extension and contraction without and within said cabinet, a flexible mattress support yieldably fitted at opposite ends with the connections between the lazy-tongs, the cabinet and the foot board, respectively, a sectional, foldable mattress on said mattress support and having fold lines remote from its ends, lifting levers on each side of the lazy-tongs pivoted on the lazy-tongs near each end thereof, respectively, and extending toward the center of the lazy-tongs, means operatively connecting the outer ends of said levers with the lazy-tongs whereby retracting the lazy-tongs lifts the inner ends of the levers, and resilient lifting members interposed between the mattress and mattress support and connecting each lever with a corresponding lever on the opposite side whereby on retraction of the lazy-tongs the mattress will be lifted along fold lines remote from the ends thereof and folding of the mattress assisted and tensioned straps connected at intervals with the lazy-tongs and underlying the mattress support intermediate with respect to the tensioned ends of said support.

BEN McKEITHAN GRAHAM.
